UNITED STATES PATENT OFFICE.

EMILIO CORTÉS, OF MEXICO CITY, MEXICO.

ELEVATOR FOR VISCOUS LIQUIDS.

Application filed March 9, 1925, Serial No. 14,310, and in Canada September 15, 1924.

This invention relates to an elevator for raising all kinds of thick liquids; like crude oil, molasses, mineral slimes, etc., some of which are difficult to pump through pipe lines under atmospheric temperature.

The adhesiveness of such thick liquids is taken advantage of for raising them, to higher levels, by conducting an endless belt of the elevator through the liquid contained in some form of a receptacle like tanks, dams, etc., and another endless belt inside the submerged belt so as to receive whatever liquid which may drop from the endless belt having contact with the liquid in the tank; both endless belts are moved vertically or almost vertically against scrapers, one of which extends into a gutter, for collecting the liquid when it has been raised to a higher level by adhering to the belts.

The endless belts are trained over pairs of pulleys, one of each pair being adjustably mounted in a bearing, while the other is permanently mounted in a bearing fastened to the tower or frame.

The higher the liquid is raised, the greater is the spilling or slopping from the submerged belt because some of the liquid always oozes down along the inside of the exterior belt; and the more it accumulates, the quicker it runs down and finally gives off lumps which are readily caught by the outside of the inner endless belt and carried to the gutter.

The object of the present invention is to extract thick liquid from low levels, for instance receptacles, tanks or dams in which the liquid has been emptied by gravity from tank cars, carrying it up to loading vats without the use of a pump nor the heating of the liquid, because the viscosity and thickness of the liquid is here useful, while in the pumping action it is an obstacle.

In the accompanying drawings:

Fig. 1 is a side view of the improved elevator.

Fig. 2 an enlarged side view of the lower part of the elevator.

Fig. 3 a side view of the upper part of elevator.

Fig. 4 a front view of same, the gutter being omitted.

Fig. 5 a front view of the gutter with the upper exterior scraper.

On the bottom of tank 1 the tower or frame 2 is mounted. In the angle irons of

the tower are adjusted two ball bearing blocks 3 suspended from two threaded stretcher rods 4. In these bearings is the lower pulley 5 journaled, and the shaft of the upper pulley 6 is journaled in the bearings 7 of the gutter 8. A fly-wheel 9 is also attached to said shaft and on the other end an idler 10 and a transmission pulley 11.

An exterior endless belt 12 is trained over the lower pulley 5 submerged into the liquid, and over the upper pulley 6. This belt 12 may pass at a very slight inclination in order that the thick liquid, which accumulates in lumps upon the belt, may fall from the belt as it rises and drop upon the outside of the interior belt 13, where it will collect and be carried to the scrapers.

The interior belt 13 passes over the lower middle pulley 14, the shaft of which is journaled in the ball bearing blocks 15 suspended from two threaded stretcher rods 16, and also over the upper middle pulley 17.

Movement is transmitted from a motor 18 by a belt 19 to revolve the lower middle pulley 14 and then by a belt 20 up to the upper exterior pulley 6.

A belt shifter 21 with chains is also attached to the elevator.

The liquid on the inside of the exterior belt 12 is taken off by an upper inner scraper 22, and falls upon the outside of the inner belt 13, and being brought over to the scraper 23, yielding held against the outside of the inner belt 13, it is discharged into the gutter or tray 24.

The liquid which remains on the outside of the exterior belt 12 passes over the pulley 6 and is taken off by the scraper 25, elastically held against the outside of said belt and likewise drops into the tray 24.

The elevating belts are moved at a relatively low speed, though the inner belt 13 has a slightly greater speed than the exterior belt 12, in order to make up for the descent of the lumps of liquid dropping from belt 12.

The velocity at which both belts are moved will depend on the altitude to which the liquid should be raised, and also upon the widths of the belts and the thickness of the liquid.

Having thus described my invention, what I claim is:

1. An elevator for viscous liquids, comprising an outer endless conveyor; an inner endless conveyor disposed wholly within the

confines of the outer conveyor in position to catch upon its outer surface liquid falling from the inner surface of said outer conveyor; and slow-speed driving means for said conveyors acting to drive the inner conveyor at a slightly greater speed than the outer.

2. An elevator for viscous liquids, comprising an outer endless conveyor; an inner endless conveyor disposed wholly within the confines of the outer conveyor in position to catch upon its outer surface liquid falling from the inner surface of said outer conveyor; a scraper yieldingly pressed against the inner surface of the outer conveyor to remove liquid adhering thereto to be caught upon the outer surface of the inner conveyor; a separate scraper yieldingly pressed against the said outer surface of the inner conveyor to remove the liquid therefrom; a discharge element to receive the liquid removed from the inner conveyor; and driving means for said conveyors.

3. An elevator for viscous liquids, comprising an outer endless conveyor; an inner endless conveyor disposed wholly within the confines of the outer conveyor in position to catch upon its outer surface liquid falling from the inner surface of said outer conveyor; separate scrapers yieldingly pressed against the outer and inner surfaces of the outer conveyor to remove liquid adhering thereto; a scraper yieldingly pressed against

the outer surface of the inner conveyor; and driving means for said conveyors.

4. The combination, with a tank to contain a viscous liquid, of an elevator for raising the liquid comprising an outer, substantially vertical, endless conveyor having its lower portion submerged in the liquid; an inner, substantially vertical, endless conveyor disposed wholly within the confines of the outer conveyor in position to catch liquid falling from the inner surface of the same but having its lower portion situated above the level of the liquid; and driving means for said conveyors.

5. An elevator for viscous liquids, comprising an outer endless conveyor; an inner endless conveyor disposed wholly within the confines of the outer conveyor in position to catch upon its outer surface liquid falling from the inner surface of said outer conveyor; a scraper yieldingly pressed against the outer surface of the inner conveyor to remove the liquid adhering thereto; a separate scraper yieldingly pressed against the outer surface of the outer conveyor to remove liquid therefrom; a discharge element to receive the liquid thus removed from both conveyors; and driving means for said conveyors.

In testimony whereof I have affixed my signature.

EMILIO CORTÉS
